(57) **CLAIM**

The ornamental design for a mousetrap, as shown and described.

DESCRIPTION

FIG. 1 is a front, left, and top perspective view of a mousetrap, showing my design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of an area labeled 9 in FIG. 1 comprising a bracket;

FIG. 10 is a partial enlarged view of an area labeled 10 in FIG. 1 comprising parts of the design;

FIG. 11 is a partial enlarged view of an area labeled 11 in FIG. 2 comprising a bracket; and,

FIG. 12 is a rear, left, and bottom perspective view of mousetrap wherein the clip is partially opened.

The broken lines shown in the drawings are included for the purpose of illustrating portions of the mousetrap that form no part of the claimed design.

The dash-dot broken lines represent the boundaries of the enlarged portions and form no part of the claimed design.
